UNITED STATES PATENT OFFICE.

WILLIAM BURGESS JOHNSON AND JOHN ALFRED JOHNSON, OF WIGAN,
COUNTY OF LANCASTER, ENGLAND.

COMPOUND LOCOMOTIVE-ENGINE.

SPECIFICATION forming part of Letters Patent No. 351,921, dated November 2, 1886.

Application filed January 15, 1886. Serial No. 189,802. (No model.)

To all whom it may concern:

Be it known that we, WILLIAM BURGESS JOHNSON and JOHN ALFRED JOHNSON, both of Wigan, in the county of Lancaster, England, 5 have invented certain new and useful Improvements in Locomotive-Engines, of which the following is a full, clear, and exact description.

The object of our invention is to provide a new and improved compound locomotive-engine.

The invention consists of the combinations of parts, including their construction, substantially as hereinafter set forth, and pointed out in the claims.

15 Reference is to be had to the accompanying drawings, forming a part of this specification, in which similar letters of reference indicate corresponding parts in all the figures.

Figure 1 is a side elevation of a locomotive 20 provided with our improvements. Fig. 2 is a plan view of the same, partly in section, the boiler and some other parts being removed. Fig. 3 represents a modification showing our improvements applied on inside cylinders. 25 Fig. 4 is a plan view of the same, partly in section. Fig. 5 represents a modification showing our improvements applied to a locomotive-engine having four cylinders abreast. Fig. 6 is a plan view of the same, partly in section, 30 the boiler being removed.

The locomotive represented in Figs. 1 and 2 has coupled driving-wheels *a*, and is provided with four outside cylinders, of which the cylinders *b* and *b'* are high-pressure cylinders and the cylinders *c* and *c'* are low-pressure cylinders. The cylinders are arranged tandem, and with the pistons of each pair of cylinders *b* and *c* and *b'* and *c'*, respectively, coupled by means of the outside crank-pins, *f* and *f'*, the piston-rods *d* and *d'*, and the connecting-rods *e* and *e'*, to the driving-wheels *a* and *a'*. The high-pressure valve *g* in the cylinder *b* and the low-pressure valve *h* in the cylinder *c* are each driven by one pair of eccentrics, *i* and *i'*, by 45 means of the reversing-link *j*, actuating the valve-rod *k* of the low-pressure valve. Each valve-rod *k* passes through a stuffing-box, *m*, at the front end of the steam-chest *l* or *l'* of the low-pressure cylinder *c* or *c'*, and is coupled to the valve-rod *k'* of the high-pressure valve *g*,

working in the valve-chest *n* of the high-pressure cylinder *b* or *b'*. Both sets of valves *g* *h* of both pairs of cylinders are reversed and the expansion regulated by one reversing-shaft, *j'*, connected with the rod *j''*, which is attached to 55 a reversing-lever operated from either quadrant or screw reversing-gear in the cab of the engine. The steam passes from the steam-pipe in the boiler through the smoke-stack and branches off into the high-pressure cylinders *b* and *b'*, which exhaust through the connecting-pipe *o* (shown in dotted lines in Fig. 1) into the steam-chests *l* and *l'* of the low-pressure cylinders *c* and *c'*. The latter exhaust into a pipe, *p*, and through an exhaust-nozzle into the 65 smoke-stack *q* of the locomotive.

Figs. 3 and 4 show our improvements attached to locomotives having inside cylinders and two pairs of driving-wheels coupled together. The valves *g* and *h* in the high and low pressure 70 cylinders are actuated directly from the connecting-rods *e* and *e'*, and the reversing of the engine is accomplished by means of the slotted links *r* *r'* in the frames *j'''*, and operated by the reversing-rod *j''* and the usual levers in the cab. 75 The arrangement of the cylinders *b* *b'* and *c* *c'* and the valves *g* and *h* is the same as above described, with the exception that the steam-chests of both the high and low pressure cylinders are fixed above instead of at the inner 80 sides of said cylinders. The double steam-chest *n'* of the high-pressure cylinders *b* and *b'* is fed directly from the boiler by a steam-pipe, *s*, and the high-pressure cylinders *b* *b'* exhaust separately, each into its respective 85 exhaust-pipe *t* or *t'*, along each side of the engine, into their respective chests *l* *l'* of the low-pressure cylinders *c* *c'*. The steam-chests *l* *l'* of the low-pressure steam-cylinders *c* *c'* communicate with one another through the passages *w*, 90 placed at each side of the exhaust-pipe *v*, and the low-pressure cylinders *c* *c'* exhaust through the exhaust-pipe *v* in the center of the smoke-stack. These inside cylinder-engine valves can be worked by means of the link-motion, rocking-shaft, and levers in any suitable manner. 95

Figs. 5 and 6 show our improvements so arranged that the cylinders are placed abreast, the high-pressure cylinders *b* *b'* being on the outside, and the two low-pressure cylinders 100

being placed between them inside of the locomotive-frame. They may also be arranged to have either the high or the low pressure cylinders outside, or one high and one low pressure cylinder alternately; but we prefer the arrangement shown, whereby the locomotive is better balanced. The cylinders *b* and *b'* and *c* and *c'* are arranged with their corresponding high and low pressure cylinder-pistons connected by the rods *e* *e'* *e''* *e'* to the cranks *f*, *f'*, *f''*, and *f'''*, which are placed at right angles to each other around the axle, so that there is one set of said cranks and their connections off the dead-center. This arrangement equalizes the strain on the axle, and the engines practically balance each other when operating, thus causing the locomotive to run with great steadiness. Each engine, as shown in Figs. 5 and 6, is arranged so that the low-pressure cylinders *c* and *c'* communicate with one another through the passages *w* at each side of the exhaust-pipe *v*. The high-pressure cylinders *b* *b'* receive their steam from the ordinary steam-pipe in the smoke-stack by means of a branch pipe extending to each side of the engine through the passages *x* *x* to the steam-chests *n*, and exhaust into the steam-chests *l* of the low-pressure cylinders by side passages, which are not shown, and the low-pressure cylinders exhaust into the pipe *v*, leading into the smoke-stack of the locomotive.

In all cases the steam-chest *l* of the low-pressure cylinder is fitted with the usual relief-valves and heating-pipes for warming the engine before starting.

Having thus fully described our invention, we claim as new and desire to secure by Letters Patent—

1. The combination, in a locomotive-engine, of four cylinders, two on each side of the engine, the high-pressure cylinders being fed directly from the boiler, each high-pressure cylinder exhausting by its own separate exhaust-pipe into the two steam-chests made common to the two low-pressure cylinders, the same being connected by a cross-pipe, the pistons both being on one rod, substantially as set forth.

2. The combination, in a locomotive-engine, of four cylinders, two high-pressure and two low-pressure, the high-pressure being fed directly from the boiler, each high-pressure cylinder having its separate exhaust-pipe leading into steam-chests common to both the low-pressure cylinders, the valves being operated by a valve-gear or link-motion, with a link to each cylinder, the pistons being coupled to the cranks and wheels, substantially as and for the purpose set forth.

The foregoing specification of our improvements in compound locomotive-engines signed by us this 15th day of December, 1885.

WILLIAM BURGESS JOHNSON.
JOHN ALFRED JOHNSON.
